G. W. PIERCE.
SPEED GOVERNOR.
APPLICATION FILED SEPT. 26, 1916.

1,295,200.

Patented Feb. 25, 1919.

UNITED STATES PATENT OFFICE.

GEORGE W. PIERCE, OF ANDERSON, INDIANA, ASSIGNOR TO THE PIERCE GOVERNOR CO.,
OF ANDERSON, INDIANA, A CORPORATION OF INDIANA.

SPEED-GOVERNOR.

1,295,200.

Specification of Letters Patent. Patented Feb. 25, 1919.

Application filed September 26, 1916. Serial No. 122,198.

To all whom it may concern:

Be it known that I, GEORGE W. PIERCE, a citizen of the United States, and resident of Anderson, in the county of Madison and 5 State of Indiana, have invented certain new and useful Improvements in Speed-Governors, of which the following is a specification.

This invention relates to certain improvements in speed limiting devices and more particularly to that type of engine governor disclosed and claimed in my co-pending application Serial No. 122,197, filed September 26, 1916.

15 My present invention involves certain improvements in the means for regulating the tension of the spring which counteracts the centrifugally actuated device and prevents the operation of the latter below a predetermined speed.

20 The object of my present invention is to so position the spring and so construct the tension regulating means as to permit of a smaller and more compact casing; to more 25 efficiently seal the spring regulating means; and to more effectively prevent tampering therewith.

Reference is to be had to the accompanying drawing in which I have illustrated one 30 embodiment of my invention, and in which similar reference characters indicate corresponding parts in the several views. In these drawings,

Figure 1 is a side elevation of a portion of 35 a motor vehicle showing one way in which my improved device may be installed;

Fig. 2 is a central longitudinal section through the device; and

Fig. 3 is a transverse section on the line 40 3—3 of Fig. 2.

Fig. 4 is a section on the line 4—4 Fig. 2.

In the specific construction illustrated, I employ a conduit section 10 provided with a tubular sleeve or extension 11 on one side 45 and integral therewith. Supported by and in axial alinement with this extension or sleeve, is a cylindrical casing including two rigidly connected parts 12 and 13. Within the casing part 13 is a centrifugally actuated device including a pair of weights 14 pivoted on the transversely extending arms 15 of a hollow shaft 16. Within the hollow shaft is a pin 17 which has one end in engagement with inwardly directed fingers or 55 lugs 18 on the weights. Thus, as the weights

swing outwardly under the influence of centrifugal force, the pin 17 is moved endwise.

The details of construction herein illustrated are substantially the same as those illustrated in my copending application 60 above referred to except that the casing is materially shorter and the spider 19 which carries the bearings for one end of the hollow shaft comes closely adjacent the end wall of the casing section 12 by reason of the 65 change in the location and method of adjustment of the spring constituting the main features of my present invention.

Within the conduit section 10 is a throttle valve 20 and upon the shaft or arbor of 70 the latter is a pinion 21 meshing with a rack bar 22 rigidly connected with the valve rod 23 abutting against the end of the pin 17. The outward movement of the centrifugal weights thus moves the rack bar to 75 toward the left from the position shown in Fig. 2 and rotates the throttle valve toward closed position.

As an important feature of my present invention, I rigidly connect a sleeve 25 to 80 the opposite end of the extension 11 from the casing and serving to inclose a regulating spring 26 and an adjusting device 27 for the latter. The outer end of the sleeve 25 is of slightly reduced diameter and within its reduced portion is threaded a plug 27. This plug is in alinement with the valve rod 23 and the coil spring is mounted between the end of the rack bar and the plug and encircles portions of each so as to remain in 85 place and normally tend to move the rack bar toward the right from the position shown. The plug is shown as being provided with a collar or flange 28 against which one end of the spring may seat. 90

The outer end of the tension regulating plug 27 is slotted and the portion in which it is mounted is provided with a pair of diametrically opposed apertures 29 which register with the opposite sides of the slot 100 twice during each rotation of the plug. The outer end of the sleeve 25 is provided with a cap 30 which prevents the threads at the end of the plug 27 from being clogged with dirt or other foreign substance. It has apertures 105 which may register with the apertures 29.

It will be noted that the spring tends to hold the weights in their inner limiting position and therefore the greater the tension 110

of the spring the greater will be the speed required to move the weights outwardly. When it is desired to regulate the tension of the spring, the cap 30 may be removed and a screw driver inserted in the end of the sleeve and into the slot of the plug 27 to rotate the latter in either direction. When the desired adjustment has been secured, the plug is left with the slot in registry with the apertures 29 and the cap 30 is placed in position with its apertures in registry with the apertures 29. Solder may then be poured in through the apertures to positively prevent the removal of the cap or the rotation of the plug, or instead of using solder, a wire may be threaded through the apertures and slot and its ends may be connected together by a lead seal or in any other suitable manner. It will be noted that the wire not only prevents the removal of the cap but also prevents any accidental rotation of the tension regulating plug.

The spring operates by compression rather than by tension as in the device shown in my companion application, and as it comes at the opposite side of the device from the casing, it is more readily accessible. Furthermore, a screw driver may readily be applied to adjust the position of the plug when required.

Various changes in the details of construction may be made within the spirit of my invention and without departing from the scope of the appended claims.

Having thus described my invention, what I claim as new and desire to secure by Letters Patent is:

1. A speed limiting device including a longitudinally movable rod, a centrifugally actuated device for moving said rod in one direction, a coil spring disposed beyond and in engagement with the opposite end of said rod for moving it in the opposite direction,

a casing inclosing said spring, a plug 48 threaded within said casing and in engagement with said spring for compressing the latter, said plug having a slot extending lengthwise thereof and said casing having an aperture in the wall thereof adapted to register with said slot, a cap for closing the end of said casing and having an aperture adapted to register with the aperture of said casing, and means extending through said apertures and said slot for preventing removal of said cap and rotation of said plug.

2. A speed limiting device including a casing, a throttle valve, a longitudinally movable rod, connections between said rod and said valve for turning the latter, a thrust member supported in said casing in alignment with said rod, a thrust spring between said thrust member and said rod, said thrust member being rotatably adjustable in the casing to vary the tension of said spring, a cap on the casing concealing the thrust member, said thrust member, cap and said casing being formed with transverse apertures, one in the form of a slot and another in the form of perforations adapted to register therewith in certain positions of rotation of said thrust member and cap, means adapted to extend through the registering apertures for locking said thrust member and cap against rotation, a centrifugally operated device for longitudinally moving said rod, and driving means connected at the outer end of said centrifugally operated device.

Signed at Anderson, in the county of Madison and State of Indiana, this 5th day of September, A. D. 1916.

GEORGE W. PIERCE.
